MAX UNGER, OF NEW YORK, N. Y.

SMOKING PIPE.

Application filed October 19, 1927. Serial No. 227,111.

This invention relates to smoking pipes and has for an object to provide a pipe with an improved bowl formed with a storage chamber in addition to the usual combustion chamber or bowl proper.

The storage chamber permits of carrying an extra supply of tobacco or other smokable product in the pipe itself, from which supply the combustion chamber or bowl proper may be readily replenished, when its contents have been consumed, without the inconvenience of resorting to some extraneous source of supply such as a pouch or can.

Another advantage of the improved construction is that the storage chamber is located in front of the combustion chamber so that the portion of the bowl which is grasped by the hand in removing the pipe from, or placing it into the mouth of the smoker remains cool to the touch. One of the disadvantages of the ordinary pipe is that the bowl becomes quite hot in smoking and consequently disagreeable to touch.

Furthermore, in practice, I have found that the combustion chamber of my improved pipe remains dry and sweet, thus affording a cool dry smoke without objectionable odor.

With these and other objects in view, the invention comprises the novel features of construction and arrangement of parts hereinafter fully described. It is to be understood that modifications may be made therein without departing from the scope of the invention as pointed out in the claims.

In the accompanying drawings, illustrating a preferred embodiment of the invention:

Figure 1 is a longitudinal sectional view of the improved bowl, with the usual stem attached thereto; and,

Fig. 2 is a top plan view of the pipe.

Referring now to the drawings, 1 indicates the bowl of the pipe formed with an interior partition wall 2 that divides the bowl-cavity into two compartments 3 and 4.

The wall 2 is preferably, though not necessarily, formed integral with the bowl, and it stops considerably short of the bottom of the bowl so as to leave an intercommunicat-

ing passage 5 between the two compartments 3 and 4.

A smoke-outlet passage 6 is formed through the neck and rear wall of the bowl 1, leading from the passage-way of the usual stem 7 and opening directly into the lower rear end of the compartment 4.

The compartment 3 constitutes the tobacco storage chamber of the improved pipe, while the compartment 4 functions as a combustion chamber, or bowl proper, in which the tobacco is consumed in smoking. These compartments are preferably so arranged that the storage chamber 3 is front of the combustion chamber 4.

In use of the pipe both the chambers 3 and 4 are filled with tobacco. The two chambers may be filled directly, or the forward end of the bowl may be inserted in a can or pouch and chambers filled by pushing the tobacco with the finger through the chamber 3 and passage 5 into the chamber 4 until both chambers are filled. The tobacco is then lighted at the top of the combustion chamber 4. When the tobacco in this chamber has been consumed it can be conveniently refilled from the extra supply carried in the storage chamber 3 by merely pushing or tamping the tobacco from the chamber 3, through the passage 5, into the chamber 4.

It is to be particularly noted that in my improved construction the suction or draft through the passage 6 is applied directly to the combustion chamber 4 and consequently the tobacco in the storage chamber 3 cannot be ignited, nor is it necessary to close or seal the opening at the top of that chamber.

I do not, of course, limit myself to the particular design of bowl shown, as the invention may be embodied in bowls of various different shapes.

What I claim is:

1. In a smoking pipe, a bowl having a transverse partition extending from the top downward part way to the bottom to divide the bowl-cavity into two compartments with a connecting passage at their lower ends, and a smoke-outlet passage through the back of

the bowl opening directly into the rear bottom portion of the bowl cavity.

2. In a smoking pipe, a bowl interiorly divided into two compartments, located one in front of the other, with an intercommunicating passage at their bottoms, the forward one of said compartments consti-

tuting a storage chamber and the rear, one a combustion chamber, and a smoke-outlet passage through the back of the bowl opening into the bottom of the rear compartment. ¹⁰

MAX UNGER.
